METHOD AND MEANS FOR CONTROLLING
HEAT TREATMENTS

André Do Huu Chan, Sceaux, France, assignor to
Société Anonyme des Manufactures de Glaces
et Produits Chimiques de Saint-Gobain,
Chauny & Cirey, Paris, France

Application August 25, 1937, Serial No. 160,921
In France August 31, 1936

13 Claims. (Cl. 49—45)

The present invention concerns heat treatments, that is to say it finds its application in all treatments making use of a cooling or heating action or articles or substances and it has for its object to ensure in a practical manner the uniformity of cooling or of heating or, at any rate, to make the variations of temperature very gradual from one point to the other of the articles treated.

It consists in effecting the heat treatment, not by the direct action of the source of cold or of heat on the article, but through the intermediary of members which move relatively to the article.

In other words, the invention consists in arranging between the source of cold or of heat and the article a member forming a screen which is continuous or not, to which is imparted a movement of displacement relatively to the article in such a manner that the zone of action of each point of the screen on the article moves on the surface of the latter.

Said movement is consequently in principle a movement of displacement parallel to the surface of the article, but it should be understood that it can be combined with other movements such, for example, as movements away from or towards the screen relatively to the article.

The movement of the screen can obey various laws according to the circumstances of the treatment. It can, for example, always be effected in the same direction in a continuous manner or in an intermittent manner. It can be alternating, periodic, it can follow an open curve or a closed curve. It can be rectilinear or curvilinear, etc.

The effects produced by the displacement of the screen in the method according to the invention are multiple.

On the one hand each point of the source of cold or of heat exerts its action on a greater surface of the article so that if the said source has thermic irregularities, for example an excess of intensity at a point, the action of said point instead of being localized on the narrow zone of the article which would correspond to a point of the screen in the fixed position and determine therein a very different temperature from that of the surrounding zones, is spread over a greater zone so that the irregularity of temperature is—if not eliminated—at any rate very much decreased. On the other hand, if for any reason the article of itself has zones which tend to become cool or heated differently from each other, the mobility of the screen enables the same point of said screen to be passed successively before

5 a hot zone and before a cold zone of the article and consequently enables said point of the screen to take up a certain part of the heat of the hot zone of the article to impart it subsequently to the cooler zone.

In a general manner the method according to the invention therefore overcomes the lack of uniformity of the source of cold or of heat, and also the lack of uniformity of the article from the thermic point of view.

Screens have already been proposed and utilized which are placed between the article to be treated and the source so as to render the action of the latter uniform, but leaving the screens stationary relatively to the article in such manner that the screen itself as regards this effect of rendering the action uniform can only act by its conductibility. This effect is consequently limited and delayed.

The present invention, on the contrary, enables as extended an effect of uniformization as desired to be obtained, and to increase the rapidity of action of the screen.

The various characteristics and advantages of the invention will, moreover, become clearly apparent in the course of the description of various embodiments of the invention given hereinafter by way of examples, with reference to the accompanying drawing.

Said examples relate to the heat treatment of sheets of glass to which the invention is advantageously applicable.

In said drawing:

Fig. 1 is a vertical longitudinal section of an annealing chamber.

Fig. 1a illustrates a modification of a detail shown in Fig. 1.

Fig. 2 is a transverse section taken through 2—2 of Fig. 1.

Fig. 3 shows in plan a modification of screens.

Fig. 4 is a vertical section of a heating oven.

Fig. 5 is a diagrammatic view showing a modification of screen.

Fig. 6 is a section of an oven to which said screen is applied.

Fig. 7 is the perspective view of another screen.

Fig. 8 is a section of an oven in which a plurality of sheets are heated of which the temperature is equalized by a single screen.

50 Figs. 1 and 2 show a sheet of glass 1 conveyed in the known manner by rollers 2 into an annealing chamber 3.

The operation to be effected herein is the cooling of the sheet. Said cooling is effected by means of the action of the walls of the chamber

which are in contact with the outer atmosphere. According to the invention, a movable screen 4 is interposed between the sheet and the walls 5 which form the source of cold. Said screen is preferably continuous. In the example shown it is composed of a series of metal blades 6 arranged close together, connected to each other by hinges and passing over guide and control drums 7.

Owing to said movable screen the cooling of the sheet is made regular, in particular between the top and the bottom of the sheet and between the edges and the centre, thereby providing a considerable improvement relatively to the results obtained with the present devices for annealing a horizontal sheet.

As shown in Fig. 1 a screen will be advantageously arranged in each of the spaces which are left free between the rollers; preferably the direction of displacement will be reversed in passing from one screen to the next.

It will be observed that the sheet 1 is in continuous movement in a direction perpendicular to that of the displacement of the screen. Consequently, the temperature is automatically made regular not only in the transverse direction but also in the longitudinal direction of the sheet, owing to the movement of the latter relatively to the screens.

In the modification of Fig. 3 which likewise relates to the treatment of a sheet of glass 1 moving in the direction of the arrow 8 the invention is carried out by means of screens 9 in the shape of discs or rings parallel to the plane of the sheet and rotating in their plane about their centre.

The action of the screen by exerting itself between the middle and the edges renders the temperature of the sheet uniform.

The examples which have just been described relate to the application of the invention to the cooling of an article such as a sheet of glass.

Various applications of the invention for heating articles will now be described.

In Fig. 4 the casing of an oven is shown at 10. A sheet to be heated, for example a sheet of glass 1, is arranged inside said oven where it is held by any appropriate means. Electric resistances 11 form the sources of heat.

According to the invention, screens 4 interposed between the sheet 1 and the sources of heat 11 are adapted to move in the direction of the arrows 12 and ensure the equalization of the temperature of the sheet.

Instead of using, as shown in Fig. 4, a screen made of plates or sheets, the screen can be formed by an assembly of juxtaposed cables, 12-13, Figs. 5 and 6, controlled so as to move in directions which are reversed from one cable to the next in such a manner that said screen as a whole does not have a single direction of displacement as that of Figs. 1 and 4 while being formed of members which move individually in a continuous manner always in the same direction.

In the devices of the previous figures the displacement of the elements of the screen takes place in the same direction. If it is desired that with its movement the screen should act in several directions, it suffices to form some of cables or ribbons arranged along a plurality of superposed layers, each of which moves in different directions. For example, two layers, 15-16, Fig. 7, will be constructed, one of which moves in a certain direction and the other in a direction at 90° relatively to the first, the aggregate of the two

layers having sufficient dimensions for the faces of the sheet 1 to be subjected in their entirety to the conjugated action of the two layers.

In Fig. 8 the oven contains a plurality of the sheets 1.

The source of heat is formed by gas burners 17. The movable screen 18, constructed for example according to one of the previously described embodiments, enables all the sheets 1 to be heated equally at all their points although said sheets are placed very differently from each other relatively to the source of heat, and the latter, furthermore, owing to its nature, is not very uniform.

15 In any case the sheet or other article can be placed in any position either vertical, horizontal or inclined according to the conditions and circumstances in which the novel method is applied.

20 In the different applications of the invention it may be advantageous to combine contact actions with the effects of radiation. For this purpose the screens can, for example, be provided with wires which come into contact with the surface of the article to be treated; such an arrangement increases the intensity of the exchanges of heat between the screen and the article and is particularly recommendable at low temperatures for which, as it is known, the exchanges by simple radiation are less active than at high temperatures, the exchanges by contact being predominant. Such an arrangement is shown in Figure 1a and illustrates the application of wire bristles 19 on the inner surface of the movable screen 4.

35 According to the applications, I can use screens made of more or less conducting materials. In certain cases metal screens are preferable, in other cases I use refractory screens.

I claim:

1. A method for rendering heat treatments uniform, consisting in transmitting the action of the source of cold or of heat to the articles to be treated, through the intermediary of members forming screens, and imparting to said members a movement relatively to the article and independently therefrom, in such a manner that the zone of action of each point of said members on the article moves on the surface of the latter in the direction along which its temperatures are intended to be equalized.

2. A method for rendering heat treatments uniform, consisting in transmitting the action of the source of cold or of heat to the articles to be treated, through the intermediary of members forming screens, and imparting to said members a movement relatively to the article independently therefrom and parallel with the surface of said article, in such a manner that the zone of action of each point of said members on the article moves on the surface of the latter in the direction along which its temperatures are intended to be equalized.

3. A device for rendering the heat treatments of articles uniform, comprising a source of cold or of heat, a member forming a screen between said source and the article to be treated, and means for imparting to said member a movement relatively to the article to be treated in the direction along which its temperatures are intended to be equalized but independently from said article.

4. A device for rendering the heat treatments of articles uniform, comprising a source of cold or of heat, a member forming a screen between

said source and the article to be treated, and means for imparting to said member a movement relatively to the article to be treated, independently therefrom, parallel with the article and in the direction along which its temperature is intended to be equalized.

5. A device for rendering uniform the heat treatments of sheet articles, comprising a source of cold or of heat, a screen formed by interconnected metal leaves located between the source and the sheet, and means for imparting to said screen a movement relatively to said sheet, parallel with the latter and in the direction along which its temperature is intended to be equalized.

6. A device for rendering uniform the heat treatments of sheet articles, comprising a source of cold or of heat, a screen forming an endless system located between the source and the sheet, and means for imparting to the screen a movement relatively to said sheet, parallel with the latter and in the direction along which its temperature is intended to be equalized.

7. A device for rendering uniform the heat treatments of sheets of glass, comprising two parallel walls in contact with the outer atmosphere, in the space between said walls a system of parallel rollers arranged in mutual spaced relation and adapted to convey sheets of glass, means for rotating said rollers in the same direction, in each of the spaces between two successive rollers a pair of parallel drums, an endless band passing over the drums of each pair, and transversely directed to the path of the sheet of glass, and means for rotating one of the drums of each pair.

8. A device for rendering uniform the heat treatments of sheets of glass, comprising two parallel walls in contact with the outer atmosphere, in the space between said walls a system of parallel rollers arranged in mutual spaced relation and adapted to convey sheets of glass, means for rotating said rollers in the same direction, in each of the spaces between two successive rollers a pair of parallel drums, an endless band passing over the drums of each pair, and transversely directed to the path of the sheet of glass,

and means for rotating one of the drums of each pair, the direction of rotation being different for two adjacent pairs.

9. A device for rendering uniform the heat treatments of sheet articles comprising a source of cold or of heat, a screen formed by an assembly of juxtaposed cables located between the source and the sheet, and means for imparting to said screen a movement relatively to the sheet, parallel with the latter and in the direction along which its temperature is intended to be equalized.

10. A device for rendering uniform the heat treatments of sheet articles, comprising a source of cold or of heat, a screen formed by an assembly of juxtaposed cables located between the source and the sheet, means for imparting to the even numbered cables a movement relatively to the sheet and parallel with the latter, and means for imparting to the odd numbered cables a movement in the opposite direction to the aforesaid movement.

15. 11. A device for rendering uniform the heat treatments of sheet articles, comprising a source of cold or of heat, a screen formed by a disc parallel to the plane of the sheet and located between the source and the sheet, and means for rotating said disc about its center.

20. 12. A device for rendering uniform the heat treatments of articles, comprising a source of cold or of heat, a member forming a screen between said source and the article to be treated, means for imparting to said member a movement relatively to the article to be treated, and flexible elements carried by the movable screen and sweeping the surface of the article to be treated.

25. 13. A plant for the heat treatment of articles comprising a tunnel, a source of heat within said tunnel, means for causing the articles to be treated to circulate in said tunnel, a movable screen forming an endless chain interposed between the articles and the walls of the tunnel, and means for imparting a movement to the endless chain formed by the screen, in a direction perpendicular to that in which the articles 30. 40. 45. circulate within the tunnel.

ANDRÉ DO HUU CHAN.
